UNITED STATES PATENT OFFICE.

RICHARD A. FINIS, OF SAN FRANCISCO, CALIFORNIA.

DESIGN FOR A VEHICLE SIGNAL-LAMP CASING.

Application filed August 16, 1924. Serial No. 10,470. Term of patent 14 years.

To all whom it may concern:

Be it known that I, RICHARD A. FINIS, a citizen of the United States, residing at San Francisco, in the county of San Francisco and State of California, have invented a new, original, and ornamental Design for a Vehicle Signal-Lamp Casing, of which the following is a specification, reference being had to the accompanying drawings, forming part thereof, in which—

Fig. 1 is a front elevation of the casing;

Fig. 2 is a side elevation thereof; and
Fig. 3 is a top plan view of the same.

The casing is to be opaque, while the lenses are of glass, of different and suitable colors.

I claim:—

The ornamental design for a vehicle signal-lamp casing, as shown.

RICHARD A. FINIS.
